US0D1015804S

(12) **United States Design Patent** (10) **Patent No.:** **US D1,015,804 S**
(45) **Date of Patent:** **** Feb. 27, 2024**

(54) **LID**

(71) Applicant: **YETI Coolers, LLC**, Austin, TX (US)

(72) Inventors: **Dustin Bullock**, Austin, TX (US); **Colin Darling**, Austin, TX (US); **Evan Goldberg**, Austin, TX (US); **Hector Barea**, Austin, TX (US)

(73) Assignee: **YETI Coolers, LLC**, Austin, TX (US)

(**) Term: **15 Years**

(21) Appl. No.: **29/807,844**

(22) Filed: **Sep. 15, 2021**

(51) LOC (14) Cl. **07-99**

(52) U.S. Cl.

USPC **D7/396.2**

(58) **Field of Classification Search**

(57) **CLAIM**

The ornamental design for a lid, as shown and described.

DESCRIPTION

FIG. 1 is a front, right, top perspective view of a lid showing our new design;

FIG. 2 is a rear, right, bottom view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front, right, top perspective, exploded view thereof;

FIG. 10 is a front view thereof;

FIG. 11 is a rear view thereof;

FIG. 12 is a right side view thereof; and,

FIG. 13 is a left side view thereof.

The broken lines in the drawings depict portions of the lid that form no part of the claimed design.

1 Claim, 8 Drawing Sheets
